DESIGN FOR A COMBINED ASH TRAY AND
GLASS HOLDER

Robert M. Stafford, Kansas City, Mo.

Application November 25, 1946, Serial No. 135,065

Term of patent 3½ years

(Cl. D85—2)

To all whom it may concern:

Be it known that I, Robert M. Stafford, a citizen of the United States, residing at Kansas City, in the county of Jackson and State of Missouri, have invented a new, original, and ornamental Design for a Combined Ash Tray and Glass Holder, of which the following is a specification, reference being had to the accompanying drawing, forming part thereof.

Fig. 1 is a perspective view of a combined ash tray and glass holder showing my new design.

Fig. 2 is a plan view of a combined ash tray and glass holder.

Fig. 3 is a side elevation of a combined ash tray and glass holder.

Fig. 4 is an end elevation of a combined ash tray and glass holder.

I claim:

The ornamental design for a combined ash tray and glass holder, as shown.

ROBERT M. STAFFORD.
